CRYSTAL WORKING APPARATUS

Richard S. Bailey, Baltimore, Md., assignor to
 Bendix Aviation Corporation, South Bend, Ind.,
 a corporation of Delaware

Application March 12, 1942, Serial No. 434,389

15 Claims. (Cl. 125—13)

This invention relates to the cutting of crystalline materials, and more particularly to the cutting of plates from a mother crystal in which the plane of the plates is oriented in accurately predetermined relationship to the crystal axes, as in the manufacture of piezo-electric quartz resonators wherein the operating characteristics of the resonator are controlled by variations in this orientation.

Piezo-electric resonators, or crystals as they are usually termed, are widely employed in the radio industry for the precise control of oscillator frequencies. These crystals are most often in the form of slabs, bars or plates which have been cut out of a mother crystal of quartz. For many years the crystal plates were cut out parallel to the optical or Z axis and perpendicular to either the X (electrical) axis or the Y (mechanical) axis, and it was found that they controlled the frequency of an oscillator very rigidly except in the presence of temperature variations. In later years it was learned that the temperature coefficient of the oscillating frequency could be controlled by rotating the plane of the cut about an axis parallel to the X axis, and it was further determined that for certain angular relations between the cutting plane and the Z axis, the temperature coefficient could be reduced substantially to zero, i. e. less than two parts per million per degree centigrade. The attainment of a temperature coefficient of this order requires the most precise determination and maintenance of the angle of the cut in production. In the manufacture of the crystals first described above having a high temperature coefficient, exact control of the cutting angle was not vitally essential, for the finished product was employed in a constant temperature oven and variations in the temperature coefficient were thus rendered innocuous. Modern apparatus, however, employs the later described low temperature coefficient crystal without the constant temperature chamber and control of the temperature coefficient is of paramount importance.

In the manufacture of the first described crystals, a bar was cut out of the mother crystal, and the surface of this bar was marked to indicate the significant axes. This bar was then placed in the cutting machine and the marks aligned with selected indices before beginning the cutting operation. This process gave a rough control of the cutting angle, but one which does not meet the exacting control requirements in the manufacture of the modern crystal element. Two prolific sources of difficulty in the old system are: the error in marking the rough bar to indicate the axes, and the error in aligning these markings with the indices on the cutting machine. These errors are seen to arise because of the need for intermediate indicial markings for the transmis-

sion of the information pertaining to the location of the crystal axes within the rough bar from the apparatus for locating those axes to the cutting machine using those axes as a reference.

5 The variations in temperature coefficient occurring when the above coarse control of the cutting plane is employed, are so great that its use in the manufacture of high grade low temperature coefficient crystals has perforce been abandoned.

10 In the first manufacture of the later described crystals, the rough bar of stock was mounted in the chuck, a sample plate of the crystal cut off, and this sample was then put through all the subsequent processing after which its temperature coefficient was measured.

If the coefficient was satisfactory, the rest of the bar was cut at the same angle or setting of the machine, but if the drift was excessive a new angle of cut was empirically selected and the above steps repeated until a satisfactory sample plate had been cut.

15 Thereafter the remaining stock was cut at the same angle as that giving the satisfactory sample. Every time cutting operations were begun on a new bar of crystal stock it was necessary to repeat the above procedure, which obviously is wasteful of time, money, and material. Up to the present time, however, the small manufacturer of crystals has been forced to cling to these inefficient methods because of the expense of X-ray apparatus for determining the crystal axis orientation, which method is described in the following paragraph.

The regular orientation of molecules within the crystal structure confers the properties of the 20 well known diffraction grating on crystalline materials for wavelengths comparable to the molecular spacing. The wavelengths required fall within that portion of the radiation spectrum which we define as X-rays. The deviation produced by a diffraction grating depends on the wavelength of the incident energy, the spacing of the grating elements, and the angle existing between the grating plane and the energy beam. When working with a given substance, such as

25 piezo-electric quartz, the spacing of the grating elements, i. e. molecules, is constant, and a monochromatic beam of X-rays is obtained by the use of selected targets in conjunction with appropriate filters. With these elements constant, the

30 crystal axes may be located by observation of the angular deviations of the diffracted beam. In operation, a plate is cut from the crystal bar, and this plate is mounted in suitable X-ray diffraction measuring equipment whereby the orientation of

35 a face or faces of the plate with respect to the crystal axes is determined. From this data a 40 correction angle is determined, should the plane of the cut not already be in the desired position, and the work holder or cutting tool may then be 45 readjusted by an amount equal to the correction

angle to provide finished crystals having the specified temperature coefficient. The X-ray apparatus required is bulky, expensive beyond the means of the small crystal manufacturer, and requires the employment of a skilled technician. In addition to this, there is the potential danger to operating personnel involved in the continuous use of X-ray apparatus.

One of the principal objects of this invention is to provide improved apparatus for accurately determining the angle between a cutting plane and the axes of the crystal stock undergoing the cutting operation, which is precise, occupies a minimum of space, and of relatively nominal cost.

Another object of this invention is to provide novel apparatus for precisely determining the angle between a cutting plane and the axes of crystal stock undergoing the cutting operation, which does not require the cutting of sample plates from the stock.

A further object of the invention is to provide novel apparatus for precisely determining the angle between a cutting plane and the axes of a crystal bar undergoing the cutting operation without removing the crystal bar from the work holder.

Still another object of the invention is to provide novel apparatus for precisely adjusting the angle between a cutting plane and the axes of a crystal bar undergoing the cutting operation in which the orientation is made without the necessity of referring to intermediate scribed lines on the bar and indicial markings on the cutting machine.

The above objects and advantages of the invention are accomplished by providing means for moving the work holder about an axis fixed with respect to the cutting plane so that the bar being cut is transferred by rotation about said axis from the working position to a position suitable for the determination of a crystal axis by the use of a stauroscope which is fixed with respect to the frame of the cutting machine, all this without removing the bar of stock from the workholder. In brief, the bar is restricted to one degree of freedom, and is moved back and forth in this degree of freedom between the working position and the means for determining crystal orientation, as required.

Other objects and advantages will in part be disclosed and in part be obvious when the following specification is read in conjunction with the drawings in which:

Figure 1 is a view in perspective of the complete cutting machine.

Figure 2 is a top view of the work holder.

Figure 3 is a view in perspective of the crystal bar mounted in the bar holder.

It is to be understood that these drawings are intended to illustrate one of the many forms in which the invention may be utilized and are not to comprise a limitation in the content or scope of the invention.

In the drawings, like parts are designated by like reference characters.

Referring to Figure 1, the base 1 carries the electric motor 2 driving the saw 3 through the medium of the motor pulley 4, the belt 5 and the saw pulley 6, the latter pulley being attached to the saw 3 by a shaft extending through the bearing 7. The housing 8 around the saw prevents the loss of excessive amounts of the abrasive used in the cutting operation. The upright 9, which is attached to the base 1, carries the holder arm 10 journalled at its upper end in the bearings 11.

The holder arm 10 may thus be rotated about the axis defined by the two bearings 11. The fixed scale 12 is secured immovably to the outer end of the arm 10, while the movable scale 14 is rigidly fixed to the slide 13 which is adjustably secured to the outer end of the arm 10 by the clamping bar screw 15. The bar of piezo-electric quartz 16 is cemented into the bar holder 17 which is secured in the bar clamp 18 by set screws (not shown). The bar clamp 18 is attached to a carrier not shown in the drawings which is longitudinally adjustable along the track in the slide 13, thereby providing a means of advancing the bar of crystal stock toward the saw 3 for the taking off of successive cuts. In addition, the entire work holder, comprising the slide 13 and the bar clamp 18 with its carrier, may, by first loosening the bar screw 15, be adjusted angularly around the axis defined by the bar screw and fixed in any desired angular position by retightening the bar screw 15.

The force with which the crystal bar 16 is fed to the saw 3 may be regulated by adjusting the position of the counterweight 19 along the counterweight arm 20, this arm being secured to the holder arm 10 as shown. At the completion of the cut, the bar 16 is prevented from falling against the housing 8 by the stop 29 located under the arm 10 and limiting its angular travel in the downward direction to the desired amount.

During the cutting operation, the work is prevented from chattering, with consequent chipping of the crystal blank, by the dash pot 34, which is connected to the holder arm 10 by the rod 35 in the manner shown, a wing nut 36 serving to attach or detach the rod 35.

Also mounted on the base 1, is the stauroscope comprising the light source 21, the polarizer indicated generally at 22, and the analyzer indicated generally at 23 with an eyepiece 30, the analyzer carrying, in addition to the polarizing element, a Calderon double plate of calcite, such as is well known in the art of crystallography for increasing the sensitivity of extinction angle indications under polarized light. The polarizer 22 is adjustable along the length of the tubular standard 24 secured to the adjustably rotatable scale plate 25. The entire stauroscope assembly may be rotated by rotating the scale plate 25 about an axis preferably passing through the line of sight of the stauroscope elements, and the angular position may be read on the scale of plate 25 in cooperation with the vernier scale 26 adjacent thereto. The thumbscrew 32 affords means for locking the assembly in any desired angular position. As the exact details of stauroscope construction are recited in many crystallographic texts, and are generally known in the art, it is not felt necessary to repeat the recitation here. The bar clamp 18 on the holder arm 10 with its associated elements may be rotated about the axis defined by the bearings 11 to the alternative position shown in dotted lines, after disconnecting the dashpot 34 by removing the wing nut 36, placing the crystal bar 16 at the working stage of the stauroscope, this stage being indicated generally at 31. The arm 10 is maintained in this position by the stop 27 attached to the upright 9.

Turning to Figure 2, the holder arm 10, with the associated elements, is shown more clearly as it appears when midway in the transfer between the cutting position and the stauroscope working stage. This view also shows the crank 28 which drives a threaded rod rotatably secured to the slide 13 and passing through a threaded

opening in the carrier for the bar clamp 18. Rotation of the crank 28 thus advances the carrier along the track in the slide 13, carrying the bar clamp 18 with it. The thickness of the blank which is cut off from the crystal bar 16 is regulated by the amount of advance given by the rotation of the crank.

The view of Figure 3 shows the crystal bar 16 mounted in the bar holder 17, plaster of Paris 33 being commonly used for the mounting operation. The bar is cut out of the mother crystal with the axes located as nearly in the position shown as possible.

In operation, the stauroscope is first adjusted. The polarizer and analyzer are crossed to provide minimum transmission of light from the source 21 to the eyepiece 30 and the Calderon double plate is then adjusted until both halves appear to be the same grey color. Briefly, the Calderon double plate consists of a plate made up of two pieces of calcite rotating the plane of polarization of a beam of polarized light in opposite directions and joined along a common bisecting line. For this reason both halves cannot appear dark simultaneously under the crossed polarizer and analyzer, and the balance of the intensity with which the two plates appear is an extremely sensitive indicator of any change in the plane of polarization of the light passing from the polarizer to the analyzer. The appearance of the Calderon double plate is unchanged only when the Z and Y axes lie parallel to the two rectangular vibration directions of the polarizer and analyzer. Therefore the intensities of the two halves of the Calderon plate appear balanced at four points as the crystal is rotated 360 degrees about an axis parallel to the X axis under the stauroscope.

During the preparation of the bar 16, all necessary cuts are made in such relation to the axes of the mother crystal that the approximate location of each of the axes within the bar is known. The bar is tested in convergent polarized light to determine whether the crystalline structure is right handed or left handed, marked accordingly, and a test is then made to determine the polarity generated along the X axis under impact, the faces normal to the X axis being marked in accordance with the results of this test. In the manufacture of one type of low temperature coefficient crystal, namely that known as the AT cut, it is required that the plane of the cut lie at plus 35 degrees to the Z axis in right handed crystals, or at minus 35 degrees to the Z axis in left handed crystals. In each case, however, the major plane surfaces of the plate are parallel to the X axis. Since it is not convenient to provide this range of adjustment in the cutting machine, the expedient adopted as a solution is to insert right handed crystal bars into the holder with the positive face up, or left handed crystal bars with the negative face up.

In the initial set up of the apparatus, the bar 16 and bar holder 17 are fastened in the bar clamp 18, and the bar so orientated that its optical axis (the Z axis) makes an angle of approximately 35 degrees with the saw blade 3. A test cut is now taken and the resulting crystal plate passed through the normal finishing processes and its temperature coefficient measured. Should the coefficient be other than the desired value, the bar screw 15 is loosened and the work holder rotated through a small angle which is conveniently read on the scales 12 and 14, thereafter retightening the bar screw 15 and taking

another cut on which the above process is repeated. This is continued until a crystal plate having the desired temperature coefficient is obtained.

5 The arm 10 and the attached work holder are now rotated to the alternative position appearing in dotted lines in Figure 1. The crystal bar is coated with an oil such as tetrahydronaphthalene to render it transparent, and the stauroscope is then orientated for balanced illumination of the Calderon plate. The reading on the scale 25 may now be recorded for future reference in the manufacture of crystals of this particular type and the stauroscope locked in this position using the thumbscrew 32. The arm 10 is now returned to the cutting position and the remainder of the bar 16 cut into plates or slabs in the usual manner. Upon the insertion of a new bar into the work holder, the arm 10 is placed in the position for stauroscopic observation, after the bar has been coated with oil, the bar screw 15 loosened and the work holder is rotated about the axis passing through the bar screw until the Calderon plate shows balanced illumination. The bar screw is now tightened, thus securing the crystal bar in the desired position, and the arm 10 is returned to the cutting position. Because of the control imposed in the original preparation of the bar from the mother crystal with respect to the approximate orientation of the axes in the bar, it is a simple matter for the operator to insure that he works only to the desired orientation of the axes among the four null or balance positions which may be obtained, by simple visual observation of the physical orientation of the bar. As an additional safeguard, the range of adjustment may be limited to less than 90 degrees but still made larger than the anticipated variation in the position of the Z axis within the bar.

40 The manufacture of BT and CT cut crystals is accomplished with equal ease once the initial reference position of the stauroscope has been determined. In setting up for subsequent production runs, the stauroscope scale 25 is set to the predetermined reference position for the particular cut of crystal being manufactured, and all bars are orientated for balanced illumination of the Calderon plate in the manner above outlined, 45 after which successive cuts of the desired thickness are taken from the bar. The saving in time and material over the first described "cut and try method" is obvious, and the adjustment of position is made directly in the machine without 50 the intermediate steps and the expensive equipment required in using X-rays for this purpose. In the apparatus disclosed, only a few seconds of time are required for adjusting the bar to within 5 or 10 minutes of the desired cutting angle.

60 While I have shown the work holder rotatably movable with respect to the stauroscope, it is obvious that the stauroscope may be made the movable element or that the separating motion may be one of translation rather than one of rotation. The results which I have achieved have been accomplished by making the stauroscope and work holder relatively movable with a single, rigidly constrained degree of freedom; that is to say, the position may be completely identified, 65 with respect to a given reference, by a single number.

70 It will be obvious that many changes and modifications may be made in the invention without departing from the spirit thereof as expressed in

the foregoing description and in the appended claims.

I claim:

1. In apparatus for the cutting of crystalline materials, a base, cutting means attached to said base, a work holder mounted on said base, and means utilizing radiant energy for locating predetermined molecular planes within a crystal located in said work holder mounted on said base, said work holder and said locating means being relatively movable with a single degree of freedom.

2. In apparatus for the cutting of anisotropic crystalline substances, a base, cutting means attached to said base, a work holder, and means utilizing light energy mounted on said base for the location of predetermined molecular planes within said substances, said work holder and said optical means being relatively movable with a single degree of freedom.

3. In apparatus for the cutting of anisotropic crystalline substances, a base, cutting means attached to said base, a work holder, and means utilizing light energy mounted on said base for the location of predetermined molecular planes within said substances, said work holder and said optical means being relatively movable between predetermined positions with a single degree of freedom.

4. In apparatus for the cutting of anisotropic crystalline substances, a base, cutting means attached to said base, a work holder, optical means for the location of crystalline axes within said substances mounted on said base, means for adjustably rotating said optical means about an axis passing through the line of sight, and means for moving said work holder and said optical means relatively within a single degree of freedom.

5. In apparatus for the cutting of anisotropic crystalline substances, a base, cutting means attached to said base, a work holder, optical means for the location of crystalline axes within said substances mounted on said base, means for moving the work holder between the working stage of said optical means and said cutting means, said means permitting movement only with a single degree of freedom, and means for adjustably rotating said work holder about an axis substantially parallel to the line of sight through said optical means when located at the working stage of said optical means.

6. In apparatus for the cutting of anisotropic crystalline substances, a base, cutting means attached to said base, a work holder, optical means for the location of crystalline axes within said substances mounted on said base, means for moving the work holder between the working stage of said optical means and said cutting means, said means permitting movement only with a single degree of freedom, and means for stopping the movement of said work holder at a predetermined point within the working stage of said optical means.

7. In apparatus for the cutting of anisotropic crystalline substances, the combination of a base, rotatable cutting means mounted on said base, optical means for the location of crystalline axes within said substances carried on said base, and a work holder movable between said cutting means and the observation stage of said optical means about an axis of rotation parallel to the axis of rotation of said cutting means.

8. In apparatus for the cutting of anisotropic

crystalline substances, the combination of rotatable cutting means, optical means for the location of crystalline axes within said substances, and a work holder movable between said cutting means and the observation stage of said optical means about an axis of rotation parallel to the axis of rotation of said cutting means, said work holder also being adjustably rotatable about an axis substantially perpendicular to said axis of rotation.

9. In apparatus for the cutting of anisotropic crystalline substances, a base, cutting means attached to said base, a work holder, and stauroscopic means mounted on said base, said work holder and said stauroscopic means being relatively movable with a single degree of freedom.

10. In apparatus for the cutting of anisotropic crystalline substances, a base, cutting means attached to said base, a work holder, stauroscopic means mounted on said base, means for adjustably rotating said stauroscopic means about an axis passing through the line of sight of said stauroscopic means, and means for moving said work holder and said stauroscopic means relatively with a single degree of freedom.

11. In apparatus for the cutting of anisotropic crystalline substances, a base, cutting means attached to said base, a work holder, stauroscopic means mounted on said base, means for moving the work holder between the working stage of said stauroscopic means and said cutting means, said means permitting movement only with a single degree of freedom, and means for adjustably rotating said work holder about an axis substantially parallel to the line of sight through said stauroscopic means when located at the working stage of said stauroscope.

12. In apparatus for the cutting of anisotropic crystalline substances, a base, cutting means attached to said base, a work holder, stauroscopic means mounted on said base, means for moving the work holder between the working stage of said stauroscopic means and said cutting means, said means permitting movement only with a single degree of freedom, and means for stopping the movement of said work holder at a predetermined point within the working stage of said stauroscopic means.

13. In apparatus for the cutting of anisotropic crystalline substances, a base, cutting means attached to said base, a work holder, and stauroscopic means mounted on said base, said work holder and said stauroscopic means being relatively movable between predetermined positions with a single degree of freedom.

14. In apparatus for the cutting of anisotropic crystalline substances, the combination of a base, rotatable cutting means mounted on said base, stauroscopic means carried on said base, and a work holder movable between said cutting means and the observation stage of said stauroscopic means about an axis of rotation parallel to the axis of rotation of said cutting means.

15. In apparatus for the cutting of anisotropic crystalline substances, the combination of rotatable cutting means, stauroscopic means, and a work holder movable between said cutting means and the observation stage of said stauroscopic means about an axis of rotation parallel to the axis of rotation of said cutting means, said work holder also being adjustably rotatable about an axis substantially perpendicular to said axis of rotation.
